(57) **CLAIM**

The ornamental design for headphones, as shown and described.

DESCRIPTION

FIG. 1 is a front view of the headphones showing front sides of a left ear piece having two buttons separated by a perpendicular feature and a right earpiece having a single button and, the right ear piece connected to the left ear piece by a flexible cord of our new design;

FIG. 2 is a rear view of the headphones showing rear sides of the left ear piece and right ear piece connected by the flexible cord;

FIG. 3 is a front view of the left ear piece;

FIG. 4 is a rear view of the left ear piece;

FIG. 5 is a left side view of the left ear piece;

FIG. 6 is a right side view of the left ear piece;

FIG. 7 is a top side view of the left ear piece;

FIG. 8 is a bottom side view of the left ear piece;

FIG. 9 is a front bottom right perspective view of the left ear piece;

FIG. 10 is a front side view of right ear piece;

FIG. 11 is a rear side view of right ear piece;

FIG. 12 is a left side view of right ear piece

FIG. 13 is a right side view of right ear piece;

FIG. 14 is a bottom side view of right ear piece;

FIG. 15 is a top side view of right ear piece; and,

FIG. 16 is a front bottom right perspective view of the right ear piece.

The broken lines in the figures show portions of the headphones that form no part of the claimed design.

The shade lines in the figures show contour and not surface ornamentation.

1 Claim, 16 Drawing Sheets
